CLAIM

The ornamental design for a fetching device for pets, as shown and described.

DESCRIPTION

FIG. 1 is a front, top, and left perspective view of a fetching device for pets, showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof; and,
FIG. 8 is a rear, bottom, and right side perspective view thereof.

The broken lines and greyed-out region illustrate portions of the article and form no part of the claimed design.

1 Claim, 8 Drawing Sheets
